CLAIM

The ornamental design for a wearable data terminal, as shown and described.

DESCRIPTION

FIG. 1 is a front perspective view of a wearable data terminal, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another top view thereof shown in environment of use.

The broken lines shown in FIG. 8 illustrate the wearable data terminal in its environment of use. The remaining broken lines depict portions of the wearable data terminal. The broken lines form no part of the claimed design.
